(57) **CLAIM**

The ornamental design for an escutcheon, as shown and described.

DESCRIPTION

FIG. 1 is a top, front, right side perspective view of an escutcheon showing my new design;

FIG. 2 is a bottom, front, left side perspective view of FIG. 1;

FIG. 3 is a front elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The broken lines showing a handle illustrate environmental structure, the remaining broken lines illustrate portions of the article; all broken lines form no part of the claimed design.
